UNITED STATES PATENT OFFICE.

THOMAS T. MITCHELL, OF JOAQUIN, TEXAS, ASSIGNOR OF ONE-HALF TO MARVIN R. CRAWFORD, OF JOAQUIN, TEXAS.

LOCK-NUT.

1,155,949.

Specification of Letters Patent.

Patented Oct. 5, 1915.

Application filed February 15, 1915. Serial No. 8,359.

To all whom it may concern:

Be it known that I, THOMAS T. MITCHELL, a citizen of the United States, residing at Joaquin, in the county of Shelby and State of Texas, have invented certain new and useful Improvements in Lock-Nuts; and I do hereby declare the following to be a full, clear, and exact description of the invention, such as will enable others skilled in the art to which it appertains to make and use the same.

This invention relates to lock nuts, and has for its object to provide a nut with novel and efficient means for reliably locking the nut against rotation upon the bolt.

With these and other objects in view, the invention consists of the novel construction, arrangement and formation of parts as will be hereinafter specifically described, claimed and illustrated in the accompanying drawing, in which:

Figure 1 represents a sectional view on the line 1—1 of Fig. 2, illustrating the lock nut applied to use. Fig. 2 represents an end elevation of the nut lock, partly in section. Fig. 3 represents a side elevation taken at right angles to Fig. 1, showing the nut partly in section. Fig. 4 represents a perspective view of one of the locking pins or keys removed. Fig. 5 represents a perspective view of a slightly modified type of locking pin, and Fig. 6 represents a perspective view of the pin locking plate removed.

Referring to the drawing in detail, where-in similar reference numerals designate corresponding parts throughout the several views, the numeral 5 indicates the shank of a bolt of the usual or any preferred construction having a head 6 at one end and screwthreads 7 extending inwardly from the opposite end. A preferred type of nut 8 is threaded upon the shank 5 and is formed with the usual internally screwthreaded bore 9 extending axially therethrough. An opening 10 is formed through the nut 8 parallel with the bore 9 thereof and is preferably rectangular in cross section, as clearly illustrated in Fig. 2, to snugly receive the pin locking plate 11 having one end rounded, as indicated at 12, and formed adjacent its opposite end with a notch 13. On one side of the rectangular opening 10 the nut 8 is formed with a pair of spaced openings 14 extending at right angles to the opening 10 and intersecting the latter and the internally

screwthreaded bore 9. On the opposite side of the rectangular opening 10, and between the openings 14, an opening 15 is formed through the nut 8 and also intersects the opening 10 and bore 9. Locking pins 16 preferably rectangular in cross section and formed with inner pointed ends 17 are slidably mounted within the openings 14 and 15 and are formed upon the longitudinal edges adjacent the opening 10 with notches 18 defining transverse shoulders 19 disposed inwardly of the inner wall of the rectangular opening 10 when the pins are operatively positioned in the nut 8. The pin locking plate 11 is removably engaged within the rectangular opening 10, engages the shoulders 19 of the locking pins and is secured against removal by a locking member 20 pivotally secured at 21 in a recess formed in the outer face of the nut and adapted to engage within the notch 13 of the plate 11. The type of locking pin illustrated in Fig. 5 is formed upon its opposite longitudinal edges with notches 22 defining transverse shoulders 23 and having its inner end 24 pointed. This type of locking pin is reversible and may be positioned to direct the pointed end 24 thereof inwardly toward the center of the bolt shank 5 or outwardly from the latter.

In use, the nut 8 is advanced to the desired position upon the threaded end of the bolt shank 5 and the several locking pins 16 are positioned within the openings 14 and 15 and are driven inwardly with a suitable tool to embed the points 24 thereof in the threads of the bolt shank 5 to reliably lock the nut against rotation. When the shoulders 19 or 23 of the locking pins are disposed flush with or inwardly of the inner wall of the rectangular opening 10 the locking plate 11 is slipped into the rectangular opening 10, engages the transverse shoulders 19 of the locking pins and thus reliably lock the latter against removal. The pivoted locking member 20 is subsequently swung to the position illustrated in Fig. 2 so as to engage within the notch 13 of the locking plate 11 and thus reliably secure the latter against loss or removal.

What I claim is:

1. A lock nut comprising a nut having an axial bore and a plurality of transverse openings intersecting said bore, a locking pin slidably mounted in each of the transverse openings having its inner end pointed,

- notches in said pins, and a plate slidably mounted in said nut adapted to engage said notches to lock said pins against removal.
2. A nut lock including a nut having an axial bore and a plurality of openings intersecting said bore, a plurality of locking pins slidably mounted in said openings and having their inner ends pointed, said nut having a rectangular opening extending parallel with the axial bore thereof and extending between several of the openings, said locking pins having notches on the longitudinal edges adjacent the rectangular opening defining transverse shoulders, a locking plate slidably mounted in said rectangular opening adapted to engage the transverse shoulders of said pins to lock the latter against removal, and a spring plate pivotally secured to the outer face of said nut adapted to engage said plate to lock the latter against removal.
3. A lock nut comprising a nut having an axial bore and a plurality of transverse openings intersecting said bore, a locking pin slidably mounted in each of the trans-

verse openings having its inner end pointed and adapted to engage in the shank of a bolt, notches formed in said pins, a plate slidably mounted in said nut for engaging and locking said pins against removal, and means for locking said plate against removal from said nut.

4. A lock nut comprising a nut having an axial bore and a plurality of transverse openings intersecting said bore, a locking pin slidably mounted in each of the transverse openings having its inner end pointed, notches formed on the longitudinal edges of said pins defining a plurality of outwardly facing shoulders, a plate slidably mounted in said nut adapted to engage behind said shoulders to lock said pins against removal, and means to lock said plate against removal from said nut.

In testimony whereof I affix my signature in presence of two witnesses.

THOMAS T. MITCHELL.
